NAIL PULLING DEVICE

Lee E. Berry and Karl C. Loehr, Chicago, Ill.

Application December 19, 1935, Serial No. 55,211

14 Claims. (Cl. 254—24)

Our invention relates to devices for pulling nails and particularly for pulling nails which have lost their head portions, and it has for its object the provision of a new and improved form and arrangement of parts by which a headless nail or the like can be gripped firmly and drawn out readily by a lever action. It is one of the objects of our invention to provide an arrangement of this type in which the gripping jaws are movable obliquely toward and from each other, in which the movement of the jaws is effected through the medium of a swingingly mounted member normally projecting beyond the end of the handle of the device, and in which such swingingly mounted member is located in position for employment as the bearing about which the device as a whole is swung for drawing out the nail, the arrangement being such that the pressure upon such swingingly mounted member in the operation of drawing out the nail serves to tighten the grip of the jaws upon the nail.

It is one of the objects of our invention to improve devices of this type in sundry details hereinafter pointed out. The preferred means by which we have accomplished our several objects are illustrated in the drawing and are herein-after specifically described. That which we believe to be new and desire to cover by Letters Patent is set forth in the claims.

In the drawing,—

Fig. 1 is a perspective view of our improved device, with the handle member broken away;

Fig. 2 is a view similar to Fig. 1 but showing a changed position of certain of the parts;

Fig. 3 is a cross sectional view through our improved device, being taken substantially at line 3—3 of Fig. 4, with parts broken away, and showing one of the hammer heads complete in addition to the parts shown in Fig. 4;

Fig. 4 is a transverse sectional view taken at line 4—4 of Fig. 3, but with both of the hammer heads broken away;

Fig. 5 is a central vertical section taken at line 5—5 of Fig. 4;

Fig. 6 is a face view of the slide plates upon which the gripping jaws of the device are mounted; and

Fig. 7 is a central vertical section through the cover plate of our improved device and the attached operating lever.

Referring now to the several figures of the drawing, in which corresponding parts are indicated by the same reference characters, 10 indicates a handle member of any approved type mounted at its end within a socket member 11

which is provided at its opposite side faces with hammer head members 12 and 13 of any approved type.

In the outer face of the plate 14 comprising one of the face portions of the socket member 11, 5 we have provided grooves 15 (see Figs. 3 and 4) which converge with respect to each other toward the adjacent end of the handle 10. Upon the outer face of said plate portion 14, we have mounted two slide members 16 and 17 which are 10 shown in the form of plates having downwardly turned flange portions 18 at their outer edges adapted by engagement with the grooves 15 to cause the slide members 16 and 17 to move toward and from each other as said members are moved 15 together longitudinally of the handle 10. As is clearly shown in Figs. 3 and 6 the member 16 is provided with a lug 19 which has sliding engagement in the notch 20 formed in the slide member 17 so as to cause the slide members 16 20 and 17 to move in unison back and forth longitudinally of the handle. Upon the ends of the slide members 16 and 17, we have provided jaw members 21 and 22 respectively in position to project outwardly from the face of the handle as 25 is best shown in Fig. 5.

In the arrangement shown, the slide members 16 and 17 are normally held in position upon the plate 14 in operative engagement with the grooves 15 by means of a cover plate 23 which is provided 30 with downwardly turned flange portions 24 and 25 at its side edges, as is best shown in Fig. 4, and with an end flange 26 as is clearly shown in Figs. 5 and 7. The cover plate 23 is also provided with an elongated opening 27 therethrough positioned 35 longitudinally of the handle 10, a downwardly projecting lug 28 being provided at one end of the opening 27 and an upwardly projecting lug 29 being provided at the opposite end. A coiled spring 30 is interposed between the lug 28 of the 40 cover plate and a transversely extending portion 31 of the slide member 17 for holding the slide members 16 and 17 normally in the position as shown in Figs. 1 and 3 corresponding to the laterally spaced arrangement of the jaw members 45 21 and 22. A seating member 32 is preferably interposed between the end of the spring 30 and the engaged portion of the slide plate 17, as is clearly shown in Figs. 3 and 5. For accommodating the spring 30 and the associated parts in position as described, a groove 33 is provided in the upper face of the plate 14, as is clearly seen in Figs. 4 and 5. The cover plate 23 is normally held in position by means of a retaining screw 34 (see Fig. 5), such screw 34 serving also to hold 50 55

a closure plate 35 in position for covering the opening 27 in the cover plate 23. One end of the closure plate 33 is notched for engaging the lug 29.

- 5 For moving the slide members 16 and 17 back and forth together longitudinally of the handle, we have provided a lever 36 in the form of a yoke which is pivotally mounted in position by means of bolts 37 passing through the arms of the yoke and through the flanges 24 and 25 of the cover plate 23. At their upper ends, the arms of the yoke are turned inwardly to provide operating lugs 38 and 39 in position to engage the jaw members 21 and 22, the arrangement being such that 10 when the lever 36 is swung from the position as shown in Fig. 1 to the position as shown in Fig. 2 the jaw members 21 and 22 and the connected slide members 16 and 17 are moved longitudinally of the handle to the position as shown in Fig. 2, 15 this movement being effected against the force of the spring 30. This longitudinal movement of the slide members 16 and 17 toward the left in Fig. 3 by the retraction of the operating lever 36 serves to move the slide members 16 and 17 trans- 20 versely toward each other, by the action of the grooves 15 upon the flanges 18, into operative gripping relation as shown in Fig. 2.

With the parts in the condition as illustrated in Fig. 1, the device is placed in position to bring 30 the jaws 21 and 22 upon opposite sides of the nail to be gripped, the device as a whole being brought into pressure engagement with the face of the member in which the nail is located. As a result of this pressure engagement of the parts, the lever 36 is moved backwardly into retracted position 35 as shown in Fig. 2, serving to bring the jaws 21 and 22 into tight gripping relation to the nail so as to be enabled to hold the nail effectively whether or not the head portion of the nail has 40 been broken away, a considerable multiplication of power being effected through the lever 36. The handle 10 is then swung about the end of the lever 36 as a fulcrum serving to draw the nail out of the member in which it is located, the 45 continued pressure upon the lever 36 having a tendency to tighten the jaws upon the nail during the operation of extracting the nail. Upon the completion of the operation, when the device is removed from the face of the board or other 50 member from which the nail has been extracted, the lever 36 is free to move again to its projected position as shown in Fig. 1, serving to loosen the jaws with respect to the extracted nail and serving to put the parts again in condition for use 55 as shown in Fig. 1.

While we prefer to employ the form of mechanism as shown in our drawing, it is to be understood that our invention is not limited to the form shown, since it is evident that changes might 60 well be made in the form and arrangement of the parts without departing from the spirit of our invention.

We claim:—

1. In a device of the type described, the combination of a handle, two jaw members, and means for mounting said jaw members on said handle and for moving them along the handle longitudinally thereof, comprises two plates mounted on the handle so as to move longitudinally thereof at one end of the handle and connected with said jaw members for holding them in position projecting outwardly from the face of the handle, and means adapted upon movements of the plates back and forth longitudinally of the handle to give the plates and the

jaw members movements toward and from each other transversely of the handle, a longitudinally movable part of said mounting and moving means for said jaw members being normally positioned beyond the end of the handle and being adapted upon movement backwardly toward the handle to effect the transverse movement of said jaw members toward each other into position to grip a headless nail. 5

2. In a device of the type described, the combination of a handle, two jaw members, and means for mounting said jaw members on said handle and for moving them along the handle longitudinally thereof, comprising two plates mounted on the handle so as to move longitudinally thereof at one end of the handle and connected with said jaw members for holding them in position projecting outwardly from the face of the handle, means adapted upon movements of the plates back and forth longitudinally of the handle to give the plates and the jaw members movements toward and from each other transversely of the handle, a longitudinally movable part of said mounting and moving means for said jaw members being normally positioned beyond the end of the handle and being adapted upon movement backwardly toward the handle to effect the transverse movement of said jaw members toward each other into position to grip a headless nail, and yielding means adapted normally to hold said plates in the position longitudinally of the handle corresponding to the transversely spaced positions of the jaw members. 10

3. In a device of the type described, the combination of a handle, jaw members projecting outwardly from one face of said handle at one end of the handle and movable toward and from each other, and means comprising a lever pivotally mounted on a transverse axis on said handle adapted by a swinging movement toward a transverse plane to move said jaw members into operative relation with each other for gripping a headless nail. 15

4. In a device of the type described, the combination of a handle, jaw members projecting outwardly from one face of said handle at one end of the handle and movable toward and from each other, and means comprising a member projecting beyond the end of the handle and movable backwardly toward the handle adapted by an operative backward stroke to move said jaw members into operative relation for gripping a headless nail. 20

5. In a device of the type described, the combination of a handle, jaw members projecting outwardly from one face of said handle at one end of the handle and movable longitudinally of the handle, cam means adapted upon movements of the jaw members together back and forth in opposite directions longitudinally of the handle to move said jaw members toward and from each other, and means comprising a member projecting beyond the end of the handle and movable backwardly toward the handle adapted by an operative backward stroke to move said jaw members longitudinally of the handle in the direction for moving them toward each other into operative relation for gripping a headless nail. 25

6. In a device of the type described, the combination of a handle, jaw members projecting outwardly from one face of said handle at one end of the handle and movable longitudinally of the handle, cam means adapted upon move- 30

ments of the jaw members together back and forth in opposite directions longitudinally of the handle to move said jaw members toward and from each other, and means comprising a lever 5 pivotally mounted on a transverse axis on said handle in position to project beyond the end of the handle and adapted by a swinging movement backwardly toward the handle to move said jaw members longitudinally in the direction 10 for moving them toward each other into operative relation for gripping a headless nail.

7. In a device of the type described, the combination of a handle, jaw members projecting outwardly from one face of said handle at one 15 end of the handle and movable toward and from each other, yielding means normally holding the parts in the position corresponding to the spaced relation positions of the jaw members, and means comprising an operating member movably 20 mounted on said handle and normally projecting beyond the end of the handle adapted upon an operative stroke into retracted position to move said jaw members toward each other into operative relation for gripping a headless nail.

25 8. In a device of the type described, the combination of a handle, jaw members projecting outwardly from one face of said handle at one end of the handle and movable longitudinally of the handle, cam means adapted upon movements of the jaw members together back and forth in opposite directions longitudinally of the handle to move said jaw members toward and from each other, yielding means normally holding said cam means in operative position for 30 holding said jaw members separated from each other, and means comprising a member projecting beyond the end of the handle and movable backwardly toward the handle adapted by an operative backward stroke to move said jaw 35 members longitudinally of the handle in the direction for moving them toward each other into operative relation for gripping a headless nail.

9. In a device of the type described, the combination of a handle, jaw members projecting outwardly from one face of said handle at one 40 end of the handle and movable toward and from each other, and means comprising a member projecting beyond the end of the handle and movable backwardly toward the handle adapted by an operative backward stroke to move said jaw members into operative relation for gripping a headless nail and normally standing in such position as to serve as a fulcrum for the extraction of a nail gripped by said jaw members, the 45 arrangement being such that the pressure on said fulcrum tends to tighten the grip of the jaw members on the nail.

10. In a device of the type described, the combination of a handle, plates mounted on said 50 handle and slidable longitudinally of the handle, guides for causing said plates to move edgewise toward and from each other as they move together longitudinally in opposite directions, jaw members carried by said plates and projecting outwardly from the face of the handle, and means 55 comprising a member projecting beyond the end of the handle and movable backwardly toward the handle adapted by an operative backward stroke to move said jaw members into operative 60 relation for gripping a headless nail.

70 11. In a device of the type described, the combination of a handle, a metal plate mounted on

the face of the handle at one end of the handle and having grooves in its outer face converging toward the adjacent end of the handle, slide members mounted on said plate and having guide means engaging said grooves for giving the 5 slide members edgewise movements toward and from each other as they move back and forth together along the plate, jaw members carried by said slide members and projecting outwardly from the face of the handle, and means for moving 10 said slide members in the direction for causing said jaw members to grip a headless nail.

12. In a device of the type described, the combination of a handle, a socket member in which said handle is mounted having grooves in its 15 outer face at one side converging toward the adjacent end of the handle, slide members mounted on said socket member and having flanges extending into said grooves for giving the slide members edgewise movements toward and from each other as they move back and forth together longitudinally of the handle, jaw members carried by said slide members and projecting outwardly from the face of the handle, and means for moving 20 said slide members in the direction for causing said jaw members to grip a headless nail.

25 13. In a device of the type described, the combination of a handle, a socket member in which said handle is mounted having grooves in its 30 outer face at one side converging toward the adjacent end of the handle, slide members mounted on said socket member and having flanges extending into said grooves for giving the slide members edgewise movements toward and from each other as they move back and forth together longitudinally of the handle, jaw members carried by said slide members and projecting outwardly from the face of the handle, and means comprising a member projecting beyond 35 the end of the handle and movable backwardly toward the handle adapted by an operative backward stroke to move said jaw members in the direction for causing said jaw members to grip 40 a headless nail.

45 14. In a device of the type described, the combination of a handle, a socket member in which said handle is mounted having grooves in its outer face at one side converging toward the adjacent end of the handle, slide members mounted 50 on said socket member and having flanges extending into said grooves for giving the slide members edgewise movements toward and from each other as they move back and forth together longitudinally of the handle, jaw members carried by said slide members and projecting outwardly from the face of the handle, yielding means normally holding said slide members at the limit of their movement in the direction for separating said jaw members, and means comprising a lever pivotally mounted on a transverse axis on said socket member in position to project beyond the end of the socket member and adapted by a swinging movement backwardly 55 toward the socket member to move said slide members longitudinally of the handle in the direction for causing said jaw members to be moved toward each other against the action of said yielding means into position to grip a headless nail.
